DESIGN FOR A TRICYCLE

Earl A. Totz, Detroit, Mich.

Application February 7, 1947, Serial No. 136,751

Term of patent 3½ years

(Cl. D34—15)

To all whom it may concern:

Be it known that I, Earl A. Totz, a citizen of the United States of America, residing at Detroit, in the county of Wayne and State of Michigan, have invented a new, original, and ornamental Design for a Tricycle, of which the following is a specification, reference being had therein to the accompanying drawing, forming a part thereof, wherein:

Figure 1 is a plan view of a tricycle, embodying my new design; and

Figure 2 is a side elevational view of the tricycle shown in Figure 1.

I claim;

The ornamental design for a tricycle, substantially as shown.

EARL A. TOTZ.
